DESIGN FOR A HAIRBRUSH

Dorothy Hertzberg, Detroit, Mich.

Application January 31, 1940, Serial No. 89,902

Term of patent 7 years

To all whom it may concern:

Be it known that I, Dorothy Hertzberg, a citizen of the United States, residing at Detroit, Wayne County, Michigan, have invented a new, original, and ornamental Design for a Hairbrush, of which the following is a specification, reference being had to the accompanying drawing, forming a part thereof, in which:

Figure 4 is an end elevational view looking towards the bristle end of the brush; and

I claim:

The ornamental design for a hairbrush, as shown.

DOROTHY HERTZBERG.
